DESIGN FOR A JEWELRY CHARM OR SIMILAR ARTICLE

James W. Taylor, Attleboro, Mass., assignor to
S. & B. Lederer Company, a corporation of Rhode Island

Application December 19, 1935, Serial No. 60,187

Term of patent 7 years

To all whom it may concern:

Be it known that I, James W. Taylor, a citizen of the United States and resident of Attleboro, Massachusetts, in the county of Bristol and State of Massachusetts, have invented a new, original, and ornamental Design for a Jewelry Charm or Similar Article, of which the following is a specification, reference being had to the accompanying drawing, forming part thereof.

In the drawing:

Fig. 1 is a plan view of a jewelry charm or similar article showing my new design; and
Fig. 2 is a side elevation thereof.

I claim:

The ornamental design for a jewelry charm or similar article substantially as shown.

Signed at Providence, in the county of Providence and State of Rhode Island this 18th day of December A. D. 1935.

JAMES W. TAYLOR.
